United States Patent Office.

GEORGE WHITTLE, OF NEW YORK, N. Y.

Letters Patent No. 70,805, dated October 29, 1867.

COAL-SCREEN.

The Schedule referred to in these Letters Patent and making part of the same.

TO ALL WHOM IT MAY CONCERN:

Be it known that I, GEORGE WHITTLE, of the city, county, and State of New York, have invented a new and useful improvement in Coal-Screens; and I do hereby declare that the following is a full, clear, and exact description thereof, which will enable those skilled in the art to make and use the same, reference being had to the accompanying drawings, forming part of this specification.

The object of this invention is to provide a cheap and simple screen whereby coal may be separated from the ashes and dust contained therein in a neat and expeditious manner, and the invention consists in constructing a cylinder-screen, and revolving the same in a tight box, and in constructing the box in a peculiar manner, so that the parts thereof are rendered otherwise useful, as will be hereinafter described.

Figure 1 is a vertical longitudinal section of the screen and its box through the line $x x$ of fig. 2.

Figure 2 is a vertical cross-section through the line $y y$ of fig. 1.

Similar letters of reference indicate corresponding parts.

A represents the screen-box, which is formed in two parts, separated at the middle, and hinged together by hook-hinges, which allow the parts to be separated. Where the two parts of the box come in contact the edges are bevelled, as seen at a , so that the parts are prevented from sliding when in use. B is the cylinder-screen. It is formed of heads, with suitable stays uniting them, and covered with wire cloth or wire screen of suitable-sized apertures for the passage of the ashes, etc. A section of this cylinder is detachable to allow access to the interior, as seen in the cross-section. This portion is marked C. This section may be secured in its place in any suitable manner.

In this example of my invention the section slides into position longitudinally, after the manner of a dovetail, in which position it is held by a button, seen at c , fig. 1. The hinges are hooks, seen at d , fig. 2, and so arranged that when the upper portion of the box is thrown back it is readily detached from the other part, or replaced when desired. When the box is closed for screening, the two parts are secured together by a hook and staple, or in any other convenient manner. D is the crank, the shaft of which may either pass through the cylinder or the crank-journal, and the pivot at the other end may be secured to the heads of the cylinder.

It will be seen that as the box divides in the middle, the cylinder can readily be removed, and the coal can be discharged therefrom into the top portion of the box, from which it may be used, or poured into the scuttle. The ashes and dust remaining in the other part of the box may be disposed of by carrying them out in the box.

It will thus be seen that with this screen the disagreeable operation of screening coal may be performed anywhere without raising a dust, and the coal-screenings and the ashes and dust be disposed of without the trouble, dust, and dirt which usually attend such operations.

Having thus described my invention, I claim as new, and desire to secure by Letters Patent—

The cylinder coal-screen B and the screen-box A, when the same are constructed, arranged, and operated substantially as shown and described, and for the purposes set forth.
